CLAIM

We claim, the ornamental design for a device for determining patency, as shown and described.

DESCRIPTION

FIG. 1 is a perspective view of a device for determining patency showing the plunger component moved outward; FIG. 2 is a perspective view of the device of FIG. 1; FIG. 3 is a front end elevational view of the device of FIG. 1; FIG. 4 is a back end elevational view of the device of FIG. 1; FIG. 5 is a right side elevational view of the device of FIG. 1; FIG. 6 is a left side elevational view of the device of FIG. 1; FIG. 7 is a top elevational view of the device of FIG. 1; FIG. 8 is a bottom elevational view of the device of FIG. 1; FIG. 9 is a perspective view of the device of FIG. 1 with the plunger component moved inward. FIG. 10 is a perspective view of the device of FIG. 9; FIG. 11 is a front end elevational view of the device of FIG. 9; FIG. 12 is a back end elevational view of the device of FIG. 9; FIG. 13 is a right side elevational view of the device of FIG. 9; FIG. 14 is a left side elevational view of the device of FIG. 9; FIG. 15 is a top elevational view of the device of FIG. 9; FIG. 16 is a bottom elevational view of the device of FIG. 9; FIG. 17 is a perspective view of the device of FIG. 1 with the plunger component moved outward and the flip-latch open; FIG. 18 a perspective view of the device of FIG. 17; FIG. 19 is a front end elevational view of the device of FIG. 17; FIG. 20 is a back end elevational view of the device of FIG. 17; FIG. 21 is a right side elevational view of the device of FIG. 17;

(Continued)

FIG. 22 is a left side elevational view of the device of FIG. 17;
FIG. 23 is a top elevational view of the device of FIG. 17;
FIG. 24 is a bottom elevational view of the device of FIG. 17;
FIG. 25 is a perspective view of the device of FIG. 1 with the plunger component moved inward and the flip-latch open;
FIG. 26 a perspective view of the device of FIG. 25;
FIG. 27 is a front end elevational view of the device of FIG. 25;
FIG. 28 is a back end elevational view of the device of FIG. 25;
FIG. 29 is a right side elevational view of the device of FIG. 25;
FIG. 30 is a left side elevational view of the device of FIG. 25;
FIG. 31 is a top elevational view of the device of FIG. 25; and,
FIG. 32 is a bottom elevational view of the device of FIG. 25.
